AUTOMATIC TANK BALL

Clarence Ricken, Chillicothe, Ill.

Application March 27, 1951, Serial No. 217,733

2 Claims. (Cl. 4—56)

1

This invention relates to toilet-hopper-and-flush-tank assemblies and more particularly to a novel flush valve therefor.

One object of the invention is to provide a novel device in which the flush valve is of spherical form and may therefore accurately seat in any of a plurality of positions instead of necessarily contacting upon the same circular area with the seat upon each closing movement, thereby giving much longer service before replacement is required.

A further object is to provide a flush valve having a depending chain to loosely hang into the water discharge elbow or pipe which connects the flush tank with the hopper, said chain serving to gravitationally guide the valve to its seat after each flushing operation.

A still further object is to provide the flush valve with a chain for connecting it to the usual valve-lifting arm of a flush tank and to make novel provision for adjustment, to provide the required length of chain between the valve and the lifting arm, according to the distance of the latter above the flush valve seat.

Another object of the invention is to provide a novel construction in which the lifting chain extends through the flush valve, and in which the above mentioned adjustment is attained by manually sliding the valve along the chain until the required chain length is obtained above the valve.

Yet another object of the invention is to provide the flush valve with yieldable means which normally engages the chain with sufficient tenacity to hold chain and valve against accidental relative sliding during flushing operation, yet will yield when the chain and valve are forcibly pulled in opposite directions by hand to adjust as above described.

Still another object is to provide the above mentioned yieldable means in the form of a plurality of detents integral with an elastic flush valve and normally engaging the chain between links of the latter, said detents providing the necessary normal connection between valve and chain and upon relative adjustment of chain and valve, yielding from their prior position and snapping in between other chain links.

A still further object is to provide a novel construction in which an elastic flush valve is moulded around a chain. In the present disclosure, this accomplishes two results, to wit: (1) the chain and valve are provided with a simple and effective operative connection; (2) the valve is provided with elastic detents en-

2

gaging between links of the chain and these detents will permit adjustment of the valve along the chain if required.

With the above and other objects in view that will become apparent as the nature of the invention is better understood, the same consists in the novel form, combination and arrangement of parts hereinafter more fully described, shown in the accompanying drawing, and claimed.

In the drawing:

Figure 1 is a perspective view, partly broken away and in section, showing a flush-tank-and-hopper assembly equipped with the improved flush valve.

Figure 2 is a fragmentary sectional view showing the valve body in the form of a hollow elastic ball connected with the chain.

Figure 3 is a view similar to Figure 1 but showing a solid elastic ball, and

Figure 4 is a detail sectional view, partly in elevation, showing one manner of providing the upper end of the chain with an attaching hook for connecting it with the valve lifting arm of a flush tank.

The construction shown in the drawing will be rather specifically described; but it is to be understood that variations may be made within the scope of the invention as claimed.

30 A flush tank is shown at 5 connected by a water discharge pipe or elbow 6 with a hopper 7. As usual, the coupling means 8 which connects the pipe or elbow 6 with the bottom of the tank 5, is provided with a flush valve seat 9. Above this seat is a flush valve lifting arm 10 operatively connected with a handle 11.

The improved flush valve is in the form of an elastic ball formed from rubber or the like, this ball being denoted at 12 in Figure 2 and at 12^a in Figure 3. The ball shown in Figure 1 may be either the ball 12 or 12^a. Due to its spherical shape, it will tightly engage the seat 9 in any of various positions instead of contacting with said seat on the same peripheral surface upon each closing movement. The wear being thus distributed over a greater area, longer service is insured before replacement is required.

A length of chain 13 is connected with the ball 12 or 12^a and extends upwardly therefrom, the upper end of said chain length 13 being provided with attaching means 14 for connecting it with the lifting arm 10. There is of course some slack in this chain length to prevent it from interfering with tight seating of the ball.

Another length of chain 15 is connected with

the ball 12 or 12^a to hang freely in the pipe or elbow 6. This chain length 15 of course ascends with the ball when a flushing operation is started, but said chain length is intended to remain at all times hanging into the pipe or elbow 6. It thus aids in gravitationally guiding the ball to its seat at the end of the flushing operation.

In the construction shown, the two chain lengths 13 and 15 are portions of a single chain, and the ball 12 or 12^a is fluid-tightly moulded around the intermediate portion of said chain. This chain is preferably a beaded chain, having spherical beads 16 loosely connected by necks 17. The ball, moulded around the chain, is thus provided with spaced spherical sockets 18 and with integral detents or ribs 19 between said sockets. The sockets 18 snugly receive the beads 16 and the detents or ribs 19 snugly embrace the necks 17 between said beads.

Due to the above described construction, the ball and chain are so tenaciously connected that there is no danger of accidental slippage of the chain through the ball during flushing operations. However, when the ball is held in one hand and the chain in the other, and said ball and chain are forcibly pulled in opposite directions, they will relatively slide. The ball and chain may thus be relatively adjusted with each to impart the proper length to the upper chain length 13 according to the height of the lifting arm 10 above the seat 9, which height is not uniform in all tanks. During the adjusting operation just explained, the detents or ribs 19 will yield to free the previously held beads 16 and at the termination of the adjusting operation, said detents or ribs will snap in between other beads, again establishing an operative connection between ball and chain. The chain is of course sufficiently long to allow maximum upward adjustment of the ball without shortening the lower chain length 15 to such an extent as to cause it to leave the pipe or elbow 6 during any flushing operation.

The ball 12 of Figure 2 is hollow, as customary with common flush valves. The upper part of this ball is provided with an integral boss 20 moulded around the chain and having the sockets 18 and detents 19. In Figure 3, the ball 12^a is solid and is moulded throughout its diameter around the chain. This ball 12^a therefore possesses a greater number of the sockets 18 and detents 19.

From the foregoing and the accompanying

drawing, it will be seen that effective provision has been made for attaining the desired ends, and while preferences have been disclosed, attention is again invited to the possibility of making variations within the scope of the invention as claimed.

What is claimed is:

1. A flush valve comprising a length of chain having means at its upper end for attaching it to the valve lifting arm of a flush tank, and a seat-engaging ball through which said chain extends fluid-tightly, said ball having yieldable means engaging said chain with sufficient tenacity to normally establish an antislipping connection between said ball and chain, yet permitting manual adjustment of the ball along the chain, said chain comprising spaced spherical beads and necks connecting said beads, said ball being formed of elastic material and having spherical sockets snugly receiving said beads, said ball also having integral ribs between said sockets and snugly surrounding said necks, said ribs constituting said yieldable means.

2. A flush valve comprising a length of chain having means at its upper end for attaching it to the valve lifting arm of a flush tank, and an elastic seat-engaging ball moulded around said chain below said attaching means and thus having integral detents engaging the chain between links thereof, said chain comprising spaced spherical links and necks connecting said links, said ball having spherical sockets snugly receiving said beads, said ball also having integral ribs between said sockets and constituting said detents; whereby a normal tenacious connection is provided between said ball and chain, yet said ball may be adjusted along said chain, during which operation said ribs will yield and snap in between other beads of the chain.

CLARENCE RICKENA.
